US00D528070S

(12) United States Design Patent (10) Patent No.: US D528,070 S
(45) Date of Patent: * Sep. 12, 2006

(54) BATTERY PACK

(75) Inventor: Wing Sum Tang, Hunghom (HK)

(73) Assignee: Samson Bright Industrial Company Limited, Kowloon (HK)

() Term: 14 Years

(21) Appl. No.: 29/232,536

(22) Filed: Jun. 21, 2005

(51) LOC (8) Cl. 13-02

(52) U.S. Cl. D13/103

(58) Field of Classification Search D13/102-106,
D13/110, 118-119, 184; D7/679; 429/96-100,
429/163, 176

See application file for complete search history.
